Primary Examiner — T. Chase Nelson*Assistant Examiner* — Mark Cavana*(74) Attorney, Agent, or Firm* — Quarles & Brady LLP**CLAIM**

The ornamental design for a training chassis for feedback-training, as shown and described.

DESCRIPTION

FIG. 1 is a front, upper, left, perspective view of training chassis for feedback-training showing my new design;

FIG. 2 is a rear, upper, right perspective view thereof;

FIG. 3 is a front elevational view thereof;

FIG. 4 is a right elevational view thereof;

FIG. 5 is a left elevational view thereof;

FIG. 6 is a rear elevational view thereof;

FIG. 7 is an upper plan view thereof; and,

FIG. 8 is a lower plan view thereof.

The broken lines are included for the purpose of illustrating portions of the training chassis for feedback-training that form no part of the claimed design.

In a preferred embodiment, the nature of this product is as an interactive training device in which the user is filmed by a camera integrated above the screen and the user's image is displayed on the monitor. While various training units are carried out, the device provides corresponding instructions for movement optimization to the user.

1 Claim, 5 Drawing Sheets---
